DESIGN FOR A BOAT

William H. Miller, Jr., South Orange, N. J.

Application June 30, 1943, Serial No. 110,572

Term of patent 14 years

(Cl. D71—1)

To all whom it may concern:

Be it known that I, William H. Miller, Jr., a citizen of the United States, residing at South Orange, in the county of Essex and State of New Jersey, have invented a certain new, original, and ornamental Design for a Boat, of which the following is a specification, reference being had therein to the accompanying drawing, forming part thereof.

Fig. 1 is a top plan view of the boat showing my new design, the front end or bow being positioned at the left.

Fig. 2 is a side elevational view of the boat.

Fig. 3 is an end elevational view taken from the bow.

I claim:

The ornamental design for a boat, as shown.

WILLIAM H. MILLER, JR.
